Int. Cl. D3—02

U.S. Cl. D87—1 R

FIG. 1

FIG. 2

FIG. 3

FIG. 4

FIG. 1 is a perspective view of a container for a canoe showing my new design;

FIG. 2 is a front plan view thereof with the top buckle in loosened position;

FIG. 3 is a side elevational view, the opposite side being a mirror image of the side shown; and

FIG. 4 is a bottom plan view thereof.

The rear is plain and unornamented except for the presence of the vertical straps which terminate just below the horizontal strap.

I claim:

The ornamental design for a container for a canoe, substantially as shown and described.
